(57) CLAIM

The ornamental design for a footwear, as shown and described.

DESCRIPTION

FIG. 1 is a perspective view of the footwear;
FIG. 2 is a left side view thereof;
FIG. 3 is a right side view thereof;
FIG. 4 is a top view thereof;
FIG. 5 is a front perspective view thereof;
FIG. 6 is a rear perspective view thereof; and,
FIG. 7 is a bottom view thereof.

The broken lines on the upper of the footwear indicate stitching and do form part of the claimed design. The broken lines on the sole of the footwear depict portions of the footwear that form no part of the claimed design.

1 Claim, 7 Drawing Sheets
